Primary Examiner — Anhdao Doan(74) *Attorney, Agent, or Firm* — Lowenstein Sandler LLP**CLAIM**

The ornamental design for an intraoral scanner wand, as shown and described.

DESCRIPTION

FIG. 1 is a perspective view of an intraoral scanner wand showing one embodiment of our new design.

FIG. 2 is a side view thereof.

FIG. 3 is a side view thereof.

FIG. 4 is a bottom view thereof.

FIG. 5 is a top view thereof.

FIG. 6 is a front view thereof; and,

FIG. 7 is a rear view thereof.

The broken lines in the drawing views are included for the purpose of illustrating portions of the intraoral scanner wand that form no part of the claimed design.
